Primary Examiner — Susan E Krakower*Assistant Examiner* — L. A. Grabenstetter(74) *Attorney, Agent, or Firm* — Muncy, Geissler, Olds & Lowe, P.C.(57) **CLAIM**

The ornamental design for a camera module, as shown and described.

DESCRIPTION

FIG. 1 is a perspective view of a camera module in accordance with the design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a second perspective view thereof, shown in a partially rotated condition.

The broken lines depicting a lens and USB connector represent unclaimed portions of the camera module.

1 Claim, 7 Drawing Sheets(56)
